J. HANLEY.
DEVICE FOR STOPPERS OF BOTTLES.

No. 12,202.

Patented Jan. 9, 1855.

UNITED STATES PATENT OFFICE.

JAMES HANLEY, OF NEW YORK, N. Y.

IMPROVEMENT IN DEVICES FOR STOPPERS OF BOTTLES.

Specification forming part of Letters Patent No. 12,202, dated January 9, 1855.

To all whom it may concern:

Be it known that I, JAMES HANLEY, of No. 13 Third Avenue, in the city and State of New York, have invented a new and improved construction of bottles by which the internal pressure is made to bear on the lengthwise surface of the cork or stopple instead of bearing against the end of the cork or stopple, as heretofore, of which the following is a specification.

By this improvement I do away with the necessity of any tie whatever for fastening the cork, which I secure by the simple act of insertion only, so that the internal force cannot displace it. This will be readily understood by reference to the accompanying drawings, where—

Figure 1 represents the neck of an ordinary bottle with its cork tied down. Figs. 2 and 3 are two modes of applying my improvement.

The same letters refer to the like parts in all the figures.

The oblique position of the bridge B in Fig. 3 allows the passage-way of the bottle to be nearly as direct as in ordinary bottles, and will be found to be more convenient in use than where the cork is inserted at right angles.

By Figs. 2 and 3 it will be seen that I make

the mouth of the bottle with a bridge, B, extending over and connecting the opposite sides of the neck of the bottle. C is the cork or stopple, which passes through the bridge B transversely to the neck of the bottle, thus effectually closing the orifice. The arrow shows the direction of the pressure as against the corks, respectively. In Fig. 1 the pressure is on the end. In Figs. 2 and 3 it is against the sides of the cork.

One very great advantage of this mode of stopping bottles that contain effervescent liquids is that it will admit of the cork being partially drawn, as shown at Fig. 4, so that a portion of the contents can be used and the cork replaced with ease and without waste of the liquor.

I claim—

The making bottles so that the resistance of their contents shall bear laterally upon the cork or stopple, also the oblique position of the bridge B, for the purposes as above set forth, in the manner stated or by its equivalent.

JAMES HANLEY.
